4 Claims. (Cl. 5—247)

The present invention relates to an independent spring mattress construction obtained by a suitable assembly of flexible elements made of wire which are all similar to each other and are such that any number of them can be joined together to form a sheet of any desired length and breadth which is rugged, light, nondeformable, silent, sanitary, easy to keep in repair and to clean.

Spring mattresses are already known in which metal is used alone or in combination with other substances; they are usually not very comfortable, heavy and noisy, difficult to keep in repair and clean and consequently insanitary. To cover the upper surface of the springs it is necessary to accumulate diverse materials to fill the empty spaces, thus increasing the weight and retaining dust. As for mattresses formed of a metal sheet stretched at its ends on a metal or wooden frame, they are particularly noisy and undergo very rapid deformations which become permanent.

These drawbacks are obviated by the construction according to the invention based on the use of resilient elements made of wire each having the shape of a recumbent M, which are deformed separately and can be flattened to more than 75% of their original height, without their various parts touching each other and without adjacent elements coming into contact, so that no noise is heard; the action of the loads is always transmitted to a certain number of elements which do not resist singly but as a whole, thereby avoiding permanent deformations of said elements and consequently of the mattress. On the other hand, the upper surface of said mattress which is formed by the upper horizontal arms of the recumbent M-shaped elements is regular and does not require complicated upholstery; moreover, said surface can be left flat, or curved at will. Furthermore, as the whole mattress construction is made up of identical elements made in series, the manufacture is simple and economical without taking into account the fact that the whole construction is flexible, light and easy to keep in repair.

In order that the invention shall be properly understood, some particular embodiments have been described hereinafter, but only by way of example, in conjunction with the accompanying drawings in which:

Figure 1 shows in perspective a resilient element alone, in the unstressed state, constituted by a recumbent M-shaped wire, and

Figure 2 shows the same element assumed to be flexed under the action of a load.

Figure 3 shows the method of assembling the

upper horizontal arm of two elements to form the beginning of a row, and

Figure 4 is a perspective view before mounting of a rivet serving for the assembly according to Figure 3.

Figure 5 is a plan view of a part of the upper surface of the mattress construction obtained by assembling several rows, and

Figure 6 is a perspective view of a portion of said mattress construction.

Figure 7 shows a usual spacing piece serving for the assembly of the mattress, and

Figures 8 to 11 illustrate modifications of assembly spacing pieces.

Figures 12 and 13 are perspective views showing the method of mounting a suspended spring mattress construction.

Figure 14 is a diagrammatic figure corresponding to a modified form of the unit of Figure 1.

Figures 15 and 16 are modified forms of the unit having a different shape.

Figure 17 is a diagrammatic view of a unit of double height, and

Figure 18 is a diagrammatic view of two units of the type shown in Figure 17 assembled to form a row on the Nuremberg scissor principle.

Referring to Figure 1, it will be seen that the resilient metallic unit E, preferably made of steel wire known as piano wire, has, as a whole, the shape of a recumbent M, having two horizontal arms, an upper one 2 and a lower one 2a, and two inclined arms 3 and 3a; this unit is formed with, for example, seven coils, one at each of the three angles, one at the outer end of each horizontal arm, and one on each horizontal arm intermediate the ends thereof.

The diameter of the coils, as well as the number of turns thereof can vary, but in general the coils 4 and 5, 4a and 5a, at the ends of the horizontal arms 2 and 2a, have the same number of turns; the intermediate coils 6, 6a and 7 also have the same number of turns as each other, the coils 4, 4a and 5, 5a having always a number of turns equal to or less than half that of the coils 6, 6a and 7. The coils 4 and 5, 4a and 5a are the coils for coupling the units E, E¹, . . . to each other; the coil 5 connected to the coil 4¹ of the adjacent element E¹ (Fig. 3) gives a number of turns less than or equal to that of the coils 6 and 7 of each unit E. Several units, thus coupled consecutively to each other, form a row T, the appearance of which in plan view, in fret form, is given by Figure 3; the coupling can be effected by means of tubular rivets 8 (Figs. 3 and 4) or by any other suitable means.

The coils 4, 5, 6, 4a, 5a, 6a of each unit E are turned so as to be inside the unit in order that after final assembly all the wires 2 on the one hand, and all the wires 2a on the other hand are in the same horizontal plane and constitute the smooth outer surfaces (upper and lower) of the mattress construction without projecting coils or parts; as illustrated, the two parallel arms 2, 2a are symmetrical with respect to the axis of the M so as to enable the units to be turned round.

The direction of winding of the wire of the coils is as indicated in Figure 1, such as to ensure that the unit is in equilibrium, the various rectangular horizontal parts of which are in pairs in two parallel vertical planes.

The coils 5, 5a and 7 which are at the ends of the acute angle of the M, form the essential resilient portions of each E unit. They offer a resistance to the collapsing of the arms 2 and 2a, 3 and 3a under the action of a load, since the collapsing of the said arms tightens these coils in the direction of winding thereof, causing resilient resistance without the deformation shown in Figure 2 remaining permanent after removal of the load.

Each row T (Fig. 3) is obtained by coupling the coil 5 of an E unit with the coil 4¹ of the following unit E¹, adjusting them so that the inclined arm 3 of the first unit E is engaged between said coils 5 and 4¹. At the bottom the coil 5a of the unit E is assembled with the corresponding coil 4a of the following unit E¹ and likewise in such a manner that the arm 3a is engaged between the said two coils.

This zig-zag coupling maintains the equilibrium of the row T in its plane during the collapsing or the rebounding of the whole row which can have any number of units and consequently any desired length which is a multiple of the length of a unit. The various arms 3 and 3a of the row form parallel chevrons.

The tubular rivet 8 is crimped so as to leave the play necessary for the flexibility of the units. In order to avoid any cause of noise by collision of the ends of the wires of the coils with each other, one or several washers made of copper or even of rubber or other suitable material can be interposed between the coupled coils for reducing the friction between the two coils; the rivet itself can be made of copper or any other suitable material. In particular cases, the coupling can also be made without washers or rivets.

The rows T, T¹ and T² prepared in advance and of the desired length, are assembled in their turn to form the spring mattress construction.

For this purpose care is taken to reverse from one row to the other the direction of the chevrons 3 and 3a; the branches of the chevrons are turned towards the left for one row T and towards the right for the following row T¹ (Fig. 6), and the coils 1 of the even and odd rows are substantially in a straight line. This reversed mounting makes for the stability of the whole construction under the action of a load.

The rows T and T¹ for example which are placed edgewise are resiliently connected to each other by steel wires or cables 9 passing through the corresponding coils of all the arms 2.

Said cables 9 are illustrated alone in Figure 6, but they would not suffice for maintaining the spacing of the rows and for fixing same. This is done by means of steel wire spacing pieces or sheaths, the turns of which touch or nearly touch each other and which are threaded on the

cables 9 between two adjacent rows; said spacing pieces are illustrated in two particular embodiments in Figures 5, 7 and 8.

Figure 7 shows the spacing piece 10 used preferably as a general spacing piece, that is to say on all the cables 9, except the marginal ones. It comprises an outer portion 11 of inner and outer diameters such that it can be threaded on the cables 9 and that it passes through the coils 4, 5 and 6; its length is so calculated that when it passes through one of said coils, which abuts against the portion 12 where the diameter increases, it projects on the other side of the coil by approximately two turns. The other end 13 of the spacing piece 10 is of a diameter such that it can just be threaded on the end 11 of the adjacent coil of the same cable 9.

A relatively perfect fixture of the rows is thus obtained while leaving them sufficient play to enable them to yield to the resilient deformations of the units E.

In Figures 5 and 8, on the end cable 9a, spacing pieces 14 of rather different shape are shown. The length of said spacing pieces is necessarily slightly greater than that of the spacing pieces 10, since the coils 4 and 5 are not doubled as in the body of the mattress; their ends are of a diameter such that they penetrate through half the coils 4 or 5 and that they contact therein with the ends of the adjacent spacing pieces. They are of greater diameter at their middle portion and the cable 9a passes freely therein, whereas it only just passes in the ends.

These spacing pieces could, moreover, have other shapes: two of them are shown in Figures 9 and 10. A steel wire sheath 15 the turns of which touch each other (Fig. 11) can also be threaded on the cable 9 consolidating said cable, and other sheaths 16 of greater diameter, cut to suitable length and serving as spacing pieces between the rows can be mounted on the first mentioned sheath between the successive rows. The sheaths 15 and 16 are integral.

The steel wire spacing pieces or sheaths can be replaced by tubes or groups of rings touching each other made of metal or other suitable material. The cable can be made of textile fibres, or a mixture, or replaced by another substance, of animal origin for example, suitable for this purpose. It can be single or multiple with parallel or twisted strands, etc.

In order to maintain the stability of the mean plane of the mattress, a cable with or without a sheath can be passed through the turns 7 which are in the same straight line, but such fixing is not absolutely necessary.

Finally, instead of spacing pieces having turns touching each other, turns almost touching each other can, as stated, be used, thereby enabling them to be moved more or less close together and to regulate the resiliency of the whole construction, by regulating the tension of the cables 9.

The cables 9 are fixed in the following manner at their ends in the case in which the mattress construction is used, for example, for a bed or a spring mattress. The end of the cable 9 passes through a rubber plug 17 (Figure 12) then through a metal washer 18 and it is held there by a knot which is soldered or not. An oval very elongated and open shaped sheet metal collar 19, cut out on one side in the form of a fork 20 having two prongs, leaves in the middle an opening for the passage of the cable 9 and of 75

the sheath 15 which abuts against the rubber plug 17 inside the collar 19. The second sheath 16 remains outside the collar and abuts against the latter, whereas on the other side it abuts 5 against the first row.

Said collar 19 is closed after the passage of the cable 9 and the sheath 15, by any suitable means. Through the various collars a metal tube 21 is then passed both for the lower row 10 and for the upper one.

The mattress construction could, moreover, be used non-suspended, without collars or tension tubes and solely as the resilient inner upholstery of a mattress for example.

15 It is understood that the resilient unit can be constructed in a fairly large number of different shapes while remaining within the limits of the invention. Figure 14 and the following illustrate some by way of examples, but their description is not limitative.

20 Figures 14, 15 and 16 show forms of units having likewise the appearance of a recumbent M, but such forms differ from that of Figure 1 by the direction of winding of the various coils and 25 consequently by the position of the various rectilinear parts 2 and 3, with respect to the mean plane of the unit. These units are assembled in rows as stated above and the rows are assembled together in the same manner.

30 The diagrammatic Figure 14 corresponds to a modification of the unit according to Figure 1, this modification consists in eliminating the coil 7 and replacing it by a simple curve 7e joining the arms 3.

35 Figures 15 and 16 are obtained from Figures 1 and 14 by arranging in the opposite direction with respect to the arms 2, the angle of the arms 3, which angle can have at its summit a coil 7f (Fig. 15) or a simple uniting curve 7g (Fig. 16).

40 Figure 17 illustrates diagrammatically a unit, the height of which has been doubled by giving it four arms 3 and by adding to the coil 7 two other coils 7h. In Figure 21 it will be seen how two units of this type can be assembled by 45 uniting three coils by means of tubular rivets 22, thereby enabling the whole construction to be deformed resiliently in accordance with the known principle of the Nuremberg scissors.

It remains, moreover, understood that these 50 various forms can be constructed with a greater number of coils and that the number of coils per arm can vary according to the development of the arms which is likewise variable.

The resilient unit can be made of wire of any 55 thickness and of wire of various shapes: round, oval, square, triangular, flat, etc. The wire can be single or in the form of cable having several strands twisted together, covered with textile materials or with rubber, or covered with a 60 winding of other wire.

The invention also concerns, by way of new 65 industrial products, the various objects which can be constructed by the use of the said mattress construction, such as spring mattresses, mattresses, seats, cushions, carpets, resilient walls and hangings for absorbing noise and vibration.

It has been stated hereinbefore that the coils 4, 4a, 5 and 5a which are the coils for coupling 70 the units together have a number of turns preferably equal to or less than half of that of the coils 6, 6a and 7; in this manner after assembly and after interposing if necessary a washer between the assembled coils 4 and 5 on the one hand, 4a and 5a on the other hand, the whole of 75

said assembled coils has the same length as the coils 6 and 6a. In this case all the coils of an assembled row have the same length and the rows are assembled together with a single type of spacing pieces, except, however, at the edges 5

It should also be noted that the recumbent M-shaped member which forms each unit can be replaced by any other equivalent member conditionally on satisfying the conditions indicated and of attaining the object aimed at.

I claim:

1. An element of a spring structure for seats, mattresses, cushions, and the like, constituted by a wire in the form of a polygon open on one side 15 and having two outer arms connected together at one of their ends by at least two inner arms, said wire having coils formed respectively at the free end and at a point intermediate the ends of each outer arm, and at the angles between the 20 arms, in such wise that each of said outer arms has three coils with coplanar axes, the coils at the ends of each outer arm having substantially half the number of turns of the intermediate coil thereof, while the axial direction of winding of 25 the coils alternates from coil to coil in each of the outer arms.

2. A spring structure for seats, mattresses, cushions and the like, comprising a plurality of elements each constituted by a wire in the form 30 of a polygon open on one side and having two outer arms connected together at one of their ends by at least two inner arms, said wire having coils formed respectively at the free end, and at a point intermediate the ends of each outer arm, 35 and at the angles between the arms, in such wise that each of said outer arms has three coils with coplanar axes, the coils at the ends of each outer arm having substantially half the number of turns of the intermediate coil thereof, while the 40 axial direction of winding of the coils alternates from coil to coil in each of the outer arms, and means for assembling said elements together in a uniformly aligned row which in plan has the form of a fret, the coils at the free ends of the 45 outer arms of an element abutting the coils at the opposite ends of the outer arms of the following element.

3. A spring structure for seats, mattresses, cushions and the like, comprising a plurality of 50 elements each constituted by a wire in the form of a polygon open on one side and having two outer arms connected together at one of their ends by at least two inner arms, said wire having coils formed respectively at the free end, and 55 at a point intermediate the ends, of each outer arm, and at the angles between the arms, in such wise that each of said outer arms has three coils with coplanar axes, the coils at the ends of each outer arm having substantially half the number 60 of turns of the intermediate coil thereof, while the axial direction of winding of the coils alternates from coil to coil in each of the outer arms, means for assembling said elements together in a uniformly aligned row which in plan has the 65 form of a fret, the coils at the free ends of the outer arms of an element abutting the coils at the opposite ends of the outer arms of the following element, and means passing through the three coils of each outer arm of an element for 70 assembling together rows of elements in parallel spaced relation.

4. A spring structure for seats, mattresses, cushions, and the like, comprising a plurality of elements each constituted by a wire in the form 75

of a recumbent M, said wire having coils formed respectively at the free end and at a point intermediate the ends of each of the outer arms of the M, and at the angles between the arms, the 5 coils at the ends of each outer arm having substantially half the number of turns of the intermediate coil thereof, while the axial direction of winding of the coils alternates from coil to coil, means for assembling said elements together in a 10 uniformly aligned row which in plan has the

form of a fret, the coils at the free ends of the outer arms of an element abutting the coils at the opposite ends of the outer arms of the following element, and means passing through the three coils of each outer arm of an element for 5 assembling together rows of elements in parallel spaced relation, the direction of the chevrons of the M being reversed from row to row.

SALOMON ROSENFELD. 10
